[57] **CLAIM**

The ornamental design for an assailant deterrent weapon, as shown and described.

DESCRIPTION

FIG. 1 is a perspective view of an assailant deterrent weapon showing my new design;

FIG. 2 is a front elevational view with the rear elevational view being a mirror image thereof;

FIG. 3 is a left side elevational view thereof;

FIG. 4 is a right side elevational view thereof;

FIG. 5 is a top view thereof; and,

FIG. 6 is a bottom view thereof.

The broken line showing of a hand in FIG. 1, is for illustrative purposes only and forms no part of the claimed design.
